UNITED STATES PATENT OFFICE.

JOHN WEST, OF CHICAGO, ILLINOIS, ASSIGNOR TO THE BARNHART BROS. & SPINDLER, OF SAME PLACE.

DESIGN FOR A FONT OF PRINTING-TYPE.

SPECIFICATION forming part of Design No. 24,700, dated September 24, 1895.

Application filed June 27, 1895. Serial No. 554,269. Term of patent 7 years.

To all whom it may concern:

Be it known that I, JOHN WEST, a citizen of the United States, residing at Chicago, county of Cook, and State of Illinois, have invented and produced a certain new and original Design for a Font of Text Type, which is fully set forth in the following specification, reference being had to the accompanying drawing, forming a part thereof.

This design comprises upper and lower case letters, Arabic numerals, character "&," dollar-mark, and points. Nearly all of the lower-case letters and many of the upper-case letters and figures are ornamented by fine-line spurs jutting from their angles and terminals at points where such spurs are not a portion of the normal or conventional outline of the letter. Straight stems and other elements terminating vertically of many of the letters are terminated in diamond swells—as, for example, lower-case f, h, i, j, k, l, m, and n, capitals F, H, I, L, T, U, V, W, and numerals 1 and 4. Many capitals are characterized by an arbitrary unconventional appendage in the form of a heavy quite extended spur jutting horizontally from the middle of the length of vertical stems, such spur being reduced to a point at the end with a barely perceptible downward curvature. Instances

of this are seen in capitals D, H, I, J, K, M, 30 N, P, R, T, U, V, W, and Y. H has its characteristic cross-stroke divided, comprising a fine line above and a heavy line below, with an open space between. Capital J has its stem doubled, comprising two heavy strokes 35 detached entirely from each other. Capital S has its circumflex provided with an entirely-detaching duplication appended below the principal line. Several capitals are characterized by a scroll or flourish which joins the main body of the letter in an abruptly-terminating swell-shade, and which ends in a fine line half-oval pointing upwardly, usually under the end of the stem to which the flourish is appended or, as in capital A, 45 under the middle of the letter. Instances of this feature, besides capital A, are capitals D, E, J, L, and X.

I claim—

The design for a font of type herein shown 50 and described.

In testimony whereof I have hereunto set my hand, in the presence of two witnesses, at Chicago, Illinois, this 11th day of June, 1895.

JOHN WEST.
